CLAIM

The ornamental design for a flying device, as shown and described.

DESCRIPTION

FIG. 1 is a front, right side perspective view of a flying device showing my new design;

FIG. 2 is a rear right side perspective view thereof;

FIG. 3 is a front, left side perspective view thereof;

FIG. 4 is a rear left side thereof;

FIG. 5 is a front view thereof;

FIG. 6 is a rear view thereof; and,

FIG. 7 is a bottom view thereof.

The broken lines shown in the drawings are for illustrative purposes only and form no part of the claim design.
